BROOM

Filed Feb. 24, 1928

Inventor:

Walter G. Manning,
Truett & DeBrock

Attorneys

UNITED STATES PATENT OFFICE

WALTER G. MANNING, OF CHICAGO, ILLINOIS, ASSIGNOR OF ONE-HALF TO ALONZO H. RANES, OF CHICAGO, ILLINOIS

BROOM

Application filed February 24, 1928. Serial No. 256,534.

My invention relates to articles of the broom type and it has for its object the provision of a new and improved arrangement of means for holding the broom head in its desired shape and for protecting the broom head from injury when used in warehouses or factories around machinery and the like.

It is one of the objects of my invention to provide a new and improved binding means to be employed in lieu of the usual stitching for holding the head material in the desired spread condition below the binding means at the upper end of the head. It is another object of my invention to provide a new and improved arrangement of shields for use in connection with my improved binding means, the arrangement being such that the shields and binding means can be applied readily by the use of a minimum amount of labor employed in connection with comparatively cheap and simple machinery.

It is one of the objects of my invention to improve devices of this type in sundry details hereinafter pointed out. The preferred means by which I have accomplished my several objects are illustrated in the drawing and are hereinafter specifically described. What I believe to be new and desire to cover by Letters Patent is set forth in the claims.

In the drawing,—

Fig. 1 is a face view of an ordinary wire bound broom provided with my improved binding and shield means, certain of the parts being broken away for clearness of illustration.

Fig. 2 is a horizontal cross section taken substantially at line 2—2 of Fig. 1.

Fig. 3 is a horizontal cross section taken at line 3—3 of Fig. 1; and

Fig. 4 is an enlarged detail view, being a section taken at line 4—4 of Fig. 1.

Referring to the several figures of the drawing, in which corresponding parts are indicated by the same reference characters,— 10 indicates the head of my improved broom formed of any suitable broom head material.

In the construction illustrated the broom head material is secured by means of wire

11 upon the lower end of a handle 12 in the ordinary approved manner.

About the broom head at a point a short distance between the upper end of the head, I have provided a metallic binder 13 for holding the broom head material in the predetermined spread condition below the top binding means, such metallic binder being used in lieu of the stitching ordinarily used in a broom of this type. In the construction illustrated, the metallic binder is in the form of a wire band tightened about the head and crimped along its opposite faces for gripping the head material so as to hold it from moving transversely from its predetermined desired spread condition. In the construction shown, the binder 13 is provided with seven inwardly extending bends at each face of the binder, a link 14 being employed at the middle bend for connecting the opposite face portions of the band through the body of the head material. The metallic binder 13 is preferably formed in the form of a band by welding and is crimped along its face portions prior to being applied upon the broom head. The binder is then applied in position by being pressed firmly into contact with the broom-corn or other broom head material by pressure upon opposite faces of the binder.

A short distance above the binder 13 and between such binder and the upper end of the broom head, I have provided a second binder 15, also preferably in the form of a wire band welded or otherwise treated for giving it the desired annular form. In the construction illustrated, the band 15 is provided with a considerably enlarged loop between the inwardly bent portions at each face of the binder, such enlarged portions being indicated by the numerals 16. These enlarged loops 16 are provided for the middle portion of the binder opposite the lower end of the handle 12 for the purpose of avoiding any possible breakage of the broom-corn or other broom head material by the application of excessive pressure thereon adjacent to the handle. The binder 15 operates in the same way as does the binder 13 for holding the broom head material firmly in position.

In the construction shown, I have employed shields 17 for the opposite sides of the broom head, such shields being held in position by the binder 15, inwardly bent portions of the binder being pressed into engagement with sockets 18 in the opposite face portions of the shields. In the construction shown, the sockets 18 are in the form of openings extending through the face portions of the shields 17. By the engagement of the inwardly projecting bends of the binder with the sockets of the shield at opposite faces of the broom head, the shield is held very securely in position.

In the construction illustrated, each of the shields 17 is formed of sheet metal which is pressed into shape for fitting over the shoulders of the broom head. Each face portion of the shield is preferably provided with outwardly pressed ribs 19 extending in diagonal position toward the binder 15 serving very materially to strengthen the shields. The shields 17 are also preferably grooved horizontally to a slight extent for receiving the binder 15, and outwardly pressed ribs 20 are provided along the outer face of the shield above and below the binder 15. The edge of the sheet metal making up the shield is preferably turned inwardly, as is best shown at 21 in Fig. 4 for exerting a stronger grip upon the broom head material.

On opposite faces of the broom head between the shields 17, I have provided flat shields 22, also preferably formed of sheet metal. In the construction shown, the shields 22 at opposite faces of the head are formed integrally with each other, being bent into form from a single sheet of material, a central opening being provided between the shield portions for mounting the device upon the handle 12 and the handle securing means at the upper end of the head. The edge portions of the shields 22 are also preferably turned inwardly, as is indicated at 23 in Fig. 4 for obtaining a stronger hold upon the broom head material. The shields 22 are secured in position at their lower ends by means of the binder 15, inwardly projecting bends of which engage sockets 24 in the shields for securing the shields firmly in position.

By the use of my invention I have provided a broom which is held very rigidly in the desired shape, the construction being such that there is very little if any danger of the structure becoming weakened by continued use. The shields 17 and 22 are held very strongly in position so as to afford ample protection for the broom head material at the points where such material would otherwise be injured by contact with machinery or other parts in the use of the broom. The arrangement is such that the binding means and shields are capable of application to a broom very quickly and easily by the use of comparatively simple machinery.

While I prefer to employ the construction as illustrated in the drawing, it will be understood that the invention is not to be limited to the exact form shown except so far as certain of the claims may be so limited by the prior art.

I claim:

1. A broom comprising in combination a bundle of broom head material, means for binding the material compactly together at the upper end of the head, a shield of sheet material extending about one edge of the head into engagement with opposite faces of the head and having a socket in the portion opposite one face, and a crimped metallic binder in the form of an endless band tightened about the head and about said shield with an inwardly projecting bend of the binder engaging said socket in the shield. 75

2. A broom comprising in combination a bundle of broom head material, means for binding the material compactly together at the upper end of the head, sheet metal shields bent about the edges of the head having horizontally disposed grooves pressed in their outer faces and having sockets in transverse alignment with said grooves, and a crimped metallic binder tightened about the head and said shields and engaging the grooves in the shields, with inwardly projecting bends of the binder engaging said sockets in the shields for holding such parts in fixed relationship. 80

3. A broom, comprising in combination a bundle of broom head material, means for binding the head material compactly together at the upper end of the head, flat shields at opposite faces of said bundle having sockets therein respectively at the same transverse plane through the head, means for securing said flat shields in position at the upper end of the head, and a crimped metallic binder tightened about the head and shields with inwardly projecting bends of the binder engaging said sockets in the flat shields for bracing them in position. 100

4. A broom, comprising in combination a bundle of broom head material, means for binding the head material compactly together at the upper end of the head and for securing a handle in position thereon, flat shields formed integrally with each other from a piece of sheet material bent upon itself and having an opening threaded on the handle means with sockets in said shields respectively at the same transverse plane through the head, and a crimped metallic binder tightened about the head and shields with inwardly projecting bends of the binder engaging said sockets in the flat shields for bracing them in position. 115

5. A broom comprising in combination a bundle of broom head material, means for binding the head material compactly together at the upper end of the head, flat shields at opposite faces of said bundle having sockets 120

therein respectively at the same transverse plane through the head, means for securing said flat shields in position at the upper end of the head, other shields of sheet material bent about the edges of the head into engagement with opposite faces of the head and having sockets in the portions at opposite faces in the same transverse plane with the sockets in said first named shields, and a crimped metallic binder tightened about the head with inwardly projecting bends of the binder engaging said sockets for bracing said shields firmly in position with respect to each other and with respect to the head.
